UNITED STATES PATENT OFFICE.

CHARLES D. GOLDEN, OF CHICAGO, ILLINOIS.

DESIGN FOR A HALL-RACK.

SPECIFICATION forming part of Design No. 26,572, dated January 26, 1897.

Application filed December 18, 1896. Serial No. 616,192. Term of patent 31 years.

To all whom it may concern:

Be it known that I, CHARLES D. GOLDEN, a citizen of the United States, residing at Chicago, in the county of Cook and State of Illinois, have invented and produced a new and original Design for Hall-Racks, of which the following is a specification, reference being had to the accompanying drawing, in which the figure is an isometric view of the front of a hall-rack, illustrating my design.

The leading feature of my design consists of a square rectangular beaded frame *a*, rounded in cross-section and raised above the plane of the general surface, within which is inclosed a raised or embossed framework *b* in the form of a rope molding foliated at the corners, as shown at *c*, the corners of the inner frame being located midway between those of the outer frame. The frame *b* in-
closes a mirror having beveled scalloped edges *d*. Located in the four corners of the outer frame are the following representations: In

the upper corner *d*, above the inner frame *b*, is formed in bas-relief a picture of Washington between two Federal flags. At the left 25 of said inner frame is shown a locomotive and railway-track, upon the right a ship and waves, and at the bottom an eagle with outstretched wings, a shield upon its breast and an olive branch in its talons. Three fanciful hooks *e e e* are shown within the corners of the frame *a* upon the respective sides of and below the inner frame *b*.

Having thus described my design, I claim—

The design for a hall-rack, substantially as 35 shown and described.

In testimony whereof I have signed this specification, in the presence of two subscribing witnesses, this 7th day of December, 1896.

CHAS. D. GOLDEN.
